UNITED STATES PATENT OFFICE.

JOSEPH K. NORTHWOOD, OF WASHINGTON, DISTRICT OF COLUMBIA.

DENTAL IMPRESSION CUP.

1,411,505.

Specification of Letters Patent.

Patented Apr. 4, 1922.

Application filed January 24, 1921. Serial No. 439,599.

To all whom it may concern:

Be it known that I, JOSEPH K. NORTHWOOD, a subject of the King of Great Britain, and have declared my intentions of becoming a citizen of the United States, and am a resident of Washington, in the District of Columbia, have invented certain new and useful Improvements in Dental Impression Cups, of which the following is a specification.

My invention relates to dental impression cups, and a purpose of my invention is the provision of a cup which can be contracted to cause the impression material to be firmly compressed against the sides of a jaw, thereby insuring a perfect impression of the jaw.

It is also a purpose of my invention to provide an impression cup in which the contracting feature is accomplished by jaws which are supported for pivotal movement at such points as to effect a uniform contraction thereof toward the front and medial portion of the cup so as to produce uniform compression of the impression material throughout the length of a jaw. Furthermore, the companion jaws are capable of being locked in contracted position and are removably associated with the body of the cup to permit of the substitution of jaws of any desired contour to suit human jaws of different contours.

I will describe three forms of impression cups embodying my invention and will then point out the novel features thereof in claims.

In the accompanying drawings:

Figure 1 is a view showing in perspective and partly disassembled, one form of impression cup embodying my invention.

Figure 2 is a perspective view showing in bottom plan the body of the cup with the companion jaws removed.

Figure 3 is a top plan view, somewhat diagrammatic, showing the companion jaws and locking means therefor.

Figure 4 is an enlarged detail perspective view of one of the companion jaws shown in Figures 1 and 2.

Figure 5 is a top plan view of another form of impression cup embodying my invention.

Figure 6 is a bottom plan view of the cup shown in Figure 5.

Figure 7 is an enlarged detail perspective view of the body of the cup shown in Figures 5 and 6.

Figure 8 is a view similar to Figure 7 showing one of the jaws and brackets comprised in the cup shown in Figures 5 and 6.

Figure 9 is a top plan view of a third form of impression cup embodying my invention.

Figure 10 is a detail perspective view of one of the sections of the cup shown in Figure 9.

Similar reference characters refer to similar parts in each of the several views.

Referring specifically to the drawings and particularly to Figures 1 and 2, B designates generally the body of the impression cup which is formed of any suitable metal and which includes a convex central portion 15 and a U-shaped lip portion 16 formed integral with and extending from the curved edge of the central portion 15. Secured to the lip 16 at points adjacent its opposite ends is a U-shaped supporting frame 17 provided at its intermediate portion with a forwardly extending handle 18 that is designed for the purpose of supporting the cup as a unit in proper position within the mouth. The frame 17 is secured to the lip 16 by means of tubular rivets 19 and in such manner that the two lips are supported in spaced parallel relation to each other as clearly shown in Figure 2.

F and F' designate companion jaws, and each of these jaws comprises a base 20 of substantially the same general curvature as the lip 16 and the frame 17. Upstanding from the outer edge of the base 20 is a flange 21, such flange being co-extensive in length with the base and of a height which may vary from one end of the flange to the other depending upon the particular contour of the jaw to which the cup is to be applied.

The base 20 has a bayonet slot 20^a at a point adjacent its rear end, such slot being adapted to receive the corresponding rivet 19 in such manner as to pivotally support the jaw as a unit for inward and outward swinging movement with relation to the cup body when effecting a contraction or expansion of the jaw. Soldered or otherwise secured to the jaws F and F' adjacent their forward ends are substantially L-shaped brackets 22 having a portion thereof extending forwardly from the jaws and provided at corresponding points with openings 22^a through which a screw-threaded fastening member 23 is adapted to extend. One end of the member 23 is provided with a head 23^a for limiting the movement of the member in one

direction through the opening. The opposite end of the member is adapted to receive a winged nut 24 which when rotated so as to feed inwardly upon the member is adapted to move the brackets 22 together and to thereby effect a contraction of the jaws F and F'.

In the applied position of the jaws F and F' to the body B of the cup, the base portions 20 are disposed between the lip 16 and the frame 17; the rivets 19 being disposed at the rear ends of the bayonet slots 20^a. In this position of the jaws, their forward ends overlap as clearly shown in Figure 1, with the brackets 22 arranged substantially in parallel relation to each other, so that by rotating the nuts 24, an inward movement of the brackets 22 is effected to cause the inward swinging of the jaws F and F' about the rivets 19 as a center.

In practice, the impression cup having been supplied with impression material is inserted into the mouth of the patient and pressed into place in the usual manner. The jaws F and F' which are in extended position are now contracted by rotation of the nut 24 so as to firmly compress the impression material against the sides of the jaw. It is to be particularly noted that because of the pivotal mounting of the jaws F and F' the contracting or drawing together thereof is toward the front or medial line of the cup, thereby exerting a uniform pressure upon the impression material so as to obtain a perfect impression of the sides of the jaw. By virtue of the fact that the fastening member 23 and the nut 24 prevent expansion or outward movement of the brackets 22, it will be clear that the jaws F and F' are locked in contracted position so that the impression material is firmly held against the sides of the jaw until it becomes set and the cup withdrawn.

As previously described, the jaws F and F' are removably associated with the cup body, it being understood that the removal of the jaws can be readily effected by so manipulating them as to remove the rivets 19 from the slots 20^a. This removability permits of the substitution of other jaws having flanges 21 of different contours, so as to render it possible to accurately fit the contour of any patient's jaw and thus secure a perfect impression.

Referring now to Figures 5, 6 and 7, I have here shown another form of impression cup embodying my invention which is used in the same manner as the first form of my invention, and is of substantially the same construction. In the present embodiment, however, the lip 16^a of the body B' of the cup is formed integral with the handle 18^a, and the ends of the lip 16^a are formed with slots 25 adapted to receive securing members 26 fixed to the jaws F² and F³ for removably

sustaining the jaws on the body. Brackets 27 and 27^a are soldered or otherwise secured to the jaws F² and F³, respectively, and each bracket is provided with a flange 28 or 28^a which is spaced from the base of the jaw so that in applied position of the jaw to the body, the flange serves to slidably retain the forward end of the jaw on the body. The bracket 27 also includes an extension 29 which is associated with the curved end of the jaw F² so as to telescopically receive between the two the confronting end of the jaw F³, it being noted that the upper edge of the flange is extended to span the space between the flange and the jaw. This arrangement of the flange obviously maintains the curved ends of the jaws F² and F³ in operative relation during the contraction of the jaws.

The brackets 27 and 27^a are formed with openings which loosely receive a threaded fastening member 30 that co-acts with a winged nut 31 to lock the jaws F² and F³ in contracted position in the same manner as the members 23 and 24 of the first form of impression cup.

Referring now to Figures 9 and 10, I have here shown a third form of impression cup which consists of two sections S and S' pivotally connected to each other by means of a pin 32. Each section S or S' includes a body portion 33, the confronting edge of which is arranged in overlapped relation with respect to the adjacent edge of the other section. The pin 32 extends through the body portions adjacent the rear end of the confronting edges in the manner shown. Each section S or S' also includes a jaw F⁵ or F⁴ formed integral with the body portion 33 or 33^a. The curved end of the jaw F⁴ is formed with a flange 34 which coacts with the jaw to telescopically receive the confronting end of the jaw F⁵ and thus maintain the ends of the jaws in operative relation to each other during expansion and contraction thereof.

The cup shown in Figures 9 and 10 is used substantially in the same manner as the other cups, it, however, being necessary in the present instance to grip the jaws themselves in effecting a contraction of the same when forcing the impression material around the sides of the jaws.

Although I have herein shown and described only three forms of impression cup embodying my invention, it is to be understood that various changes and modifications may be made herein without departing from the spirit of the invention and the spirit and scope of the appended claims.

What I claim is:

1. An impression cup comprising, a body, jaws pivotally supported on the body in a manner to permit of their being contracted toward the front and medial portion of the body, and means adapted to be arranged ex-

teriorly of the mouth for moving and maintaining the jaws in contracted position.

2. An impression cup comprising, a body, jaws pivotally supported on the body and 5 removably associated therewith, said jaws being capable of occupying expanded and contracted positions, and means for moving the jaws to and maintaining the same in contracted position, said means comprising 10 brackets secured to the jaws, a member extending loosely through the brackets, and a nut engageable with the member.

3. An impression cup comprising, a body including a U-shaped lip, a U-shaped frame 15 secured and arranged in spaced relation to said lip, a handle carried by the frame, a pair of jaws pivotally supported between the frame and lip to occupy expanded and contracted positions, and means carried by 20 the jaws for moving and maintaining the jaws in contracted position.

4. An impression cup comprising, a body including a lip of U-form, a frame of U-form arranged in spaced parallel relation to the 25 lip, rivets extending through said lip and frame at points adjacent their opposite ends, jaws having bayonet slots formed therein to receive said rivets in a manner to cause the rivets to pivotally support the jaws between 30 said frame and lip, means carried by the jaws for drawing the same together, and a handle formed on said frame.

5. An impression cup comprising, a body including a U-shaped lip, a U-shaped frame

arranged in spaced parallel relation to the 35 lip, rivets extending through the frame and lip at points adjacent their opposite ends, jaws pivotally supported by said rivets for inward and outward swinging movement between said frame and lip, each of said jaws 40 comprising a curved base portion having a bayonet slot formed therein, and a flange upstanding from the base portion and co-extensive in length therewith, brackets carried by the forward ends of the flanges, and 45 means engageable with the brackets for drawing the forward ends of the jaws together.

6. An impression cup comprising, a body including a lip having slots formed therein, 50 a pair of jaws, pins carried by the jaws and insertable in said slots for pivotally supporting the jaws upon the body, means for tele-scopically associating the curved ends of the jaws, and means for moving and maintain- 55 ing the jaws in contracted position.

7. An impression cup comprising, a body, jaws removably and pivotally supported upon the body, brackets secured to the jaws and including retention flanges, slidably em- 60 bracing the body, an extension formed on one of the brackets and spaced from the corresponding jaw to slidably receive between the two the confronting end of the other jaw, and means extending through the 65 brackets for moving and maintaining the jaws in contracted position.

JOSEPH K. NORTHWOOD.
